UNITED STATES PATENT OFFICE

LEON F. MEUNIER, OF CLEVELAND, OHIO, ASSIGNOR TO CHICAGO PNEUMATIC TOOL COMPANY, OF NEW YORK, N. Y., A CORPORATION OF NEW JERSEY

SWITCH MECHANISM

Application filed August 24, 1926. Serial No. 131,194.

This invention relates to control apparatus for electrical motors and machinery. While having features of general application, it has been developed as an improved form of the 5 locking switch disclosed and claimed in my prior Patent No. 1,586,953 issued June 1, 1926.

One object of the invention is to provide totally inclosed and protected electrical control devices. Another object is to adapt the ordinary snap switch to be totally inclosed while still indicating its operating condition. Other objects will be apparent from the detailed description which follows.

15 In order to illustrate the invention and the manner of its construction and use, a preferred embodiment thereof is shown in the accompanying drawings, in which:

Fig. 1 is a vertical sectional view through a 20 control unit having a plurality of electrical switches;

Fig. 2 is a top plan view of the unit shown in Fig. 1;

25 Figs. 3 and 4 are top plan views of the snap switch illustrating the manner of securing an operating member to the switch shaft in a predetermined position;

Fig. 5 is a plan view of the operating member for the snap switch prior to its attachment to the switch shaft;

Fig. 6 is a sectional view of the operating member shown in Fig. 5 substantially on the line 6—6 of Fig. 5;

Fig. 7 is a vertical sectional view of the 35 shaft extension member for the snap switch taken on the line 7—7 of Fig. 8;

Figs. 8 and 9 are respectively bottom plan and top plan views of the shaft extension member;

40 Fig. 10 is a diagrammatic development of the cam provided on the shaft extension member.

The embodiment of the invention chosen for the purpose of illustration is an electrical control unit A adapted to be secured in any suitable manner as by bolts a to the casing B (Fig. 2) of a coal drill, motor, or other electrical device. The unit comprises a casing 11, which may be in two or more parts, totally 45 inclosing a plurality of electrical switches to

which power is supplied from a cable C (Fig. 2) entering the unit through a junction box D. The switches comprise a main switch 12 of the ordinary snap type operated by a rotatable handle 13 and a reversing switch 55 E operated by a control handle e projecting beyond the casing and pivoted at e' therewith for limited swinging movement.

As in my prior Patent No. 1,586,953, means are provided under control of main switch 12 60 for locking reversing switch handle e against movement when the main switch is "on", such means comprising a plunger f arranged to be projected across the path of movement of handle e by a lever g controlled by a cam h. 65 Since this portion of the locking mechanism forms no part of the present invention, further description thereof is omitted.

As shown in Figs. 1 and 2, casing 11 entirely incloses snap switch 12 so that the "On" 70 and "Off" indicia thereon are not visible as in my aforementioned patent and the usual snap switch control member cannot be used. The new control arrangement and the manner and means by which the condition of the main 75 switch is indicated to the operator comprising the present invention will now be described.

It is necessary first to provide an operating member for snap switch 12 having a fixed and 80 known relation to the "on" and "off" positions of the latter. To this end the ordinary snap switch button is removed, and an annular member 14 (Figs. 5 and 6) provided with a centrally disposed transversely projecting hub portion 14^a through which extends a threaded bore 14^b is substituted. Member 14 is threaded upon shaft 12^a of snap switch 12 until the top of the member is flush with the top of the shaft. Member 14 is then 85 fixed to the shaft by boring a small hole through the member and through shaft 12^a and inserting a pin 15 (Figs. 3 and 4). With switch 12 in the "on" position equal segments of member 14 are cut away on opposite 90 sides of said member along chords in substantial parallelism with the greatest dimension of window 12^c through which the "On" and "Off" indicia is visible, whereupon member 14 becomes a substantially oblong actuating 95 100

member fixed to switch shaft 12^a in a predetermined relation.

Actuating member 14 is received with a loose sliding fit between ears 16^a projecting from the lower side of the switch shaft extension member or post 16 (Figs. 1, 7, 8 and 9). Post 16 is rotatably received in a bearing 11^a in casing 11 and receives on its reduced projecting end 16^b the switch actuating knob or handle 13 which is keyed to the post 16 by a key number 17 (Fig. 1) and is retained on the post by nut 18. Post 16 adjacent the inner end of bearing 11^a is formed with an annular flange 16^c from which projects cam *h* for controlling the operation of locking lever *g*. Flange 16^c and cam *h* are preferably formed as integral portions of post 16.

Key 17 fixes operating handle 13 to post 16 in a definite relation so that indicating means upon handle 13, such as projections 13^a (Fig. 2), indicate to the operator the condition of main switch 12. With the structural arrangement herein described, main switch 12 is "on" when the handle is in the position shown in Fig. 2,—that is, when the projections 13^a are substantially transverse to reverse switch handle *e*. In this position, locking plunger *f* is in the position shown in Fig. 1 preventing movement of reversing switch handle *e*. As additional means for exactly determining the "on" and "off" positions of the main switch, the upper face of flange 16^c is provided with a series of depressions or sockets 19 arranged to be engaged by a plunger 20 slidably received in a bore in casing 11 adjacent to and parallel with bearing 11^a. Plunger 20 is yielding-ly forced into engagement with flange 16^c by spring 21.

Fig. 10 shows the development of cam *d*, which has a series of stops *d'* (Figs. 9 and 10) preventing reverse rotation of main switch control handle 13 to such a position as would release the locking plunger *f* to permit the throwing of reversing handle *e* while the switch is "on".

From the above it will be apparent that the present invention provides a motor control device incorporating the cheap but efficient snap switch, but totally inclosing and protecting the same from dust and foreign matters, and that the herein described structural arrangement and method of installation enables the operator to know the condition of such snap switch in spite of its being totally inclosed.

While a preferred form of the invention has been herein shown and described it is to be understood that the invention is not limited to the specific details thereof, but covers all changes, modifications, and adaptations within the scope of the appended claims.

I claim as my invention:

1. In combination, a snap switch having a shaft rotatable in one direction only, a casing

completely inclosing said switch, an actuating member for said switch having a bearing in said casing, said member having a loose connection with said switch shaft, said connection being arranged to establish a predetermined fixed relation whereby the condition of said switch is known by the position of said member. 70

2. In combination, a snap switch having a shaft rotatable in one direction only and a plurality of "on" and "off" positions, a casing completely inclosing said switch, an actuating member for said switch having a bearing in said casing, said member having a loose connection with said switch shaft, said connection being arranged to establish a predetermined fixed relation whereby the condition of said switch is known by the position of said member, and stop means for said member corresponding with the stop positions of said switch. 75 80 85

3. In combination, a snap switch having a shaft rotatable in one direction only, a casing completely inclosing said switch, an actuating member for said switch having a bearing in said casing, said member having a loose connection with said switch shaft, said connection being arranged to establish a predetermined fixed relation whereby the condition of said switch is known by the position of said member, and cooperating means on said casing and said member providing yielding stops for the latter corresponding with the stop positions of said switch. 90 95

4. In combination, a snap switch having a shaft rotatable in one direction only, a casing completely inclosing said switch, an actuating member for said switch having a bearing in said casing, said member having a loose connection with said switch shaft, said connection being arranged to establish a predetermined fixed relation whereby the condition of said switch is known by the position of said member, and stop means for said member corresponding with the stop positions of said switch comprising a spring pressed plunger on said casing and sockets in said member to receive said plunger. 100 105 110

5. In combination, a snap switch having a shaft rotatable in one direction only and a plurality of "on" and "off" positions during one complete rotation, a casing completely inclosing said switch, an actuating member for said switch having a bearing in said casing, interengaging means on said shaft and said member establishing a fixed relation whereby the condition of said switch is known by the position of said member. 115 120

6. In combination, a snap switch having a shaft rotatable in one direction only, a casing completely inclosing said switch, an actuating member for said switch having a bearing in said casing, a block fixedly secured to said shaft, and means on said member releasably engaging said block in a fixed rela- 125 130

tion whereby the condition of said switch is known by the position of said member.

7. In combination, a snap switch having a shaft rotatable in one direction only, a casing completely inclosing said switch, an actuating member for said switch having a bearing in said casing, a block fixedly secured to said shaft, and lugs on said member receiving said block therebetween to establish a fixed relation between said switch and said member.

10 8. An electrical control device, comprising a casing, a snap switch and a reversing switch inclosed by said casing, an actuating member 15 rotatably mounted in said casing, means controlled by said member for locking said reversing switch, and means connecting said snap switch and said actuating member in a predetermined fixed relation whereby said member indicates the condition of said switch 20 and actuates said locking means in the "on" position of said snap switch.

9. An electrical control device, comprising a casing, a snap switch and a reversing switch 25 inclosed by said casing, an actuating member rotatably mounted in said casing, means controlled by said member for locking said reversing switch, interengaging means on the shaft of said snap switch and on said actuating member for establishing a driving connection therebetween in a fixed relation 30 whereby said member indicates the condition of said switch and actuates said locking means in the "on" position of said snap 35 switch.

10. An electrical control device comprising a casing, a snap switch and a reversing switch inclosed by said casing, an actuating member 40 rotatably mounted in said casing, means controlled by said member for locking said reversing switch, a block fixedly secured to the shaft of said snap switch, lugs on said actuating member receiving said block therebetween establishing an operating connection 45 whereby said member indicates the condition of said snap switch and actuates said locking means in the "on" position of said snap switch.

11. An electrical control device comprising 50 a casing, a snap switch and a reversing switch inclosed by said casing, an actuating member rotatably mounted in said casing, means controlled by said member for locking said reversing switch, interengaging means on the 55 shaft of said snap switch and on said actuating member for establishing a driving connection therebetween in a fixed relation, and stop means for said member corresponding with the stop positions of said snap switch.

60 12. An electrical control device comprising a casing, a snap switch and a reversing switch inclosed by said casing, an actuating member 65 rotatably mounted in said casing, means controlled by said member for locking said reversing switch, means connecting said

70 snap switch and said actuating member in a predetermined fixed relation, and cooperating means on said casing and said member providing yielding stops for the latter corresponding with the stop positions of said snap switch.

75 13. An electrical control device comprising a casing, a snap switch and a reversing switch inclosed by said casing, an actuating member rotatably mounted in said casing, means controlled by said member for locking said reversing switch, including an annular flange on said member carrying a cam, a block fixedly secured to the shaft of said snap switch, lugs on said actuating member receiving said block therebetween to establish an operating connection, and stop means for 80 said member comprising a spring-pressed plunger in said casing and sockets in the flange of said member to receive said plunger.

85 Signed by me at Cleveland, in the county of Cuyahoga and State of Ohio, this 9th day of August, 1926.

LEON F. MEUNIER.
